UNITED STATES PATENT OFFICE.

CHARLES WHITE, OF NEW YORK, N. Y.

ADJUSTABLE BAT TIE.

Application filed October 11, 1920. Serial No. 416,258.

To all whom it may concern:

Be it known that I, CHARLES WHITE, a citizen of the United States, residing in borough of Queens, city of New York, in the 5 State of New York, have invented certain new and useful Improvements in Adjustable Bat Tie, of which the following is a specification, reference being had to the accompanying drawings, forming a part hereof.

10 It has been proposed formerly to provide bat ties and neck ties with devices for permitting their adjustment to length, but such devices have not been satisfactory either for the wearer or the manufacturer. They have 15 usually included a buckle of some sort and have necessitated the doubling of some part of the fabric or the over-lapping thereof in such manner as to create a bulging or inflexible section which prevents the tie from 20 slipping in the collar and oftentimes presses upon the neck of the wearer. Such adjusting devices have been expensive for the manufacturer since they entail a great deal of special hand work. The result is that to- 25 day it is usual to make up bat ties in five different standard lengths adapted, roughly for necks of varying sizes. This condition requires the dealer to keep an unduly large stock of patterns on hand and does not meet 30 the requirements of the particular wearer nicely since the length can necessarily be only an approximation for different collar sizes. The object of the present invention is to obviate this condition by providing an 35 entirely practicable bat tie capable of adjustment to length by the user and so constructed as to satisfy manufacturing requirements. Ties as now constructed comprise two plies. In the improved construc- 40 tion the tie is formed in two sections and the end of one section is provided with a pocket between the two plies and the end of the other section is provided with a flexible but stiffened tongue adapted to enter the 45 said pocket and to be clamped therein by means of a suitable buckle or other retaining device. The tongue, in the interest of cheapness, can be formed by laying in a piece of cardboard, celluloid or other suitable ma- 50 terial between the two plies of one section of the tie and stitching it in place. The invention will be described in greater detail in connection with the illustrated embodiment thereof shown in the accompanying drawings, in which—

Figure 1 is a view in perspective of a tie

constructed in accordance with the invention, the two sections being separated.

Figure 2 is a fragmentary detail view in section through the meeting ends of the tie 60 shown in Figure 1, and taken on the plane indicated by the line 2—2 of Figure 1, looking in the direction of the arrows.

Figure 3 is a fragmentary detail view in section showing the tongue clamped in the 65 pocket.

The improved scarf is made in two sections, *a*, *b*, adapted to be engaged adjustably at their rear ends to form a tie of suitable length. The rear end of one of these 70 sections *a* is so stitched as to form between its plies an open ended pocket indicated at *a'* while the rear end of the other section *b* is formed with a relatively stiff but flexible tongue indicated at *b'* and adapted to 75 enter the pocket *a'*. The tongue *b'* can be formed most conveniently and with the least expense by stitching between the plies of the section *b*, a piece of cardboard, celluloid, or other suitable stiff but flexible material, indicated at *b*². When the tongue *b'* is inserted in the pocket *a'* to an extent depending upon the desired length of the tie it must be clamped therein by some means 80 which are operable readily for subsequent 85 readjustment if needed and such clamping means must be of such character and so related to the sections of the tie as to conform readily to the shape thereof and slide freely between the folds of the collar. The invention is not to be limited to the precise character of such clamping devices but it contemplates the provision of devices having the characteristics noted. Such clamp is indicated by way of example in Figure 2, as 90 comprising a metallic buckle *c* stitched to the fabric at the end of the section *a* and forming a mouth for the pocket *a'* and carrying a hinged clamping piece *c'* which can be moved by the finger to engage the tongue 100 *b'* when in place or release it for withdrawal.

In using the improved tie it will be understood that the length of the sections *a*, *b*, will be such as to accommodate necks of any 105 size so that a range of sizes need not be carried in stock by the dealer nor considered by the purchaser. The clamp *c'* when swung into open position as shown in Figure 2, permits the tongue *b'* to be slid into the 110 pocket *a'* to an extent sufficient to form a tie of proper over-all length for the wearer.

The clamp c' is then manipulated to clinch the section b in adjusted relation. When the clamp c' is moved into closed position it will lie along the section a and will not impede free movement of the tie in the collar.

5 The construction described is inexpensive for the manufacturer, relieves the dealer of the burden of different stock sizes and permits the wearer to readily adjust the length 10 of the tie to satisfy his individual taste.

What I claim is:

1. A tie of fabric formed in two separable sections having one section made up with two plies of fabric so stitched as to form 15 an open pocket in the material, said pocket formed with a metal mouth, a flexible but stiff tongue formed in the fabric at the end of the other section and adapted to be inserted in said pocket for a greater or less 20 distance and means carried by said metal mouth and operable to engage the tongue

when inserted in the pocket and to hold the two sections fixedly in such relation to give an overall predetermined length to fit the neck of the wearer.

25

2. A tie of fabric formed in two separable sections, one of said sections having an open pocket formed in the fabric at its rear end, said pocket formed with a metal mouth, a tongue of cardboard formed in the rear end 30 of the other section stitched between the plies thereof and adapted to enter said pocket, a buckle stitched at the end of the pocket and having a lever operable normally to engage the tongue when inserted in the 35 pocket to hold the two sections fixedly in such relation to give an overall predetermined length to fit the neck of the wearer.

This specification signed this 9th day of October A. D., 1920.

CHARLES WHITE.
